The ornamental design for a holdback for drapery curtain, as shown and described.

DESCRIPTION

FIG. 1 is a perspective view of a holdback for drapery curtain showing my new design;

FIG. 2 is a front elevational view thereof;

FIG. 3 is a side elevational view thereof; and,

FIG. 4 is a rear elevational view thereof.

The broken line showing of the stem attachment for the holdback in FIG. 1 is for illustrative purposes only and forms no part of the claimed design.
